TABLE LAMP

Albert M. Lorenzo, Wyckoff, N.J., assignor to Mial Manufacturing Corporation, Bethpage, N.Y., a corporation of New York

Filed Sept. 15, 1966, Ser. No. 3,872

Term of patent 14 years

(Cl. D48—20)

FIG. 1

FIG. 2

FIG. 3

FIG. 5

FIG. 3 is a top plan view thereof;

FIG. 4 is a perspective view thereof with the lamp head and support arm broken away for convenience of illustration;

I claim:

The ornamental design for a table lamp, as shown and described.
